UNITED STATES PATENT OFFICE

WILLIAM WALLACE ROWE, OF CINCINNATI, OHIO, ASSIGNOR TO THE PAPER SERVICE COMPANY, OF LOCKLAND, OHIO, A CORPORATION OF OHIO

BARREL LINER AND PROCESS OF FORMING SAME

Application filed January 21, 1928. Serial No. 248,488.

My invention relates to a novel type of barrel liner and to a novel method of folding barrel liners.

In the art there are several distinct types of barrel liners, each of which has many modifications. There is in the first place a tube made from creped paper which is open both at the top and bottom. Secondly there is a tube made of creped paper open at the top only, and with a circular disc-like portion of creped paper sewed to the bottom. A third class is what may be called the bag type, which is made from an integral sheet of paper folded on itself and then stitched with a seam along the side and at the bottom.

My invention has for its object the provision of a liner of the bag type which may be readily inserted in a container and which will be free to expand so as to conform to the shape of the barrel.

The above and other objects to which reference will be made in the ensuing disclosure I accomplish by that certain combination and arrangement of parts of which I have shown a preferred embodiment.

Referring to the drawings:—

Figure 1 is a perspective view of a liner of my improved type, with portions thereof cut away to show the internal structure and the preferred manner in which the bag is folded.

Figure 2 is a sectional view taken along the lines A—A in Figure 1.

Figure 3 is a plan view of my liner as it appears from above when inserted within a barrel, the barrel being concealed by the upper folded over edge of the liner.

The liner is made from a sheet of crinkled or creped paper folded over on itself with a line of stitching forming a side seam 1 and another line of stitching forming a bottom closure with a seam 2. The liner prior to folding will have the general appearance of a bag which may be folded flat with the side edges formed on one side along the seam 1 and on the other by the portion of the bag opposite the seam 1. In folding the bag into shape the edges of the bag are folded inwardly thus forming four lines of fold which are indicated at 3. The bottom corner ears

4 are then tucked in against the seam 2 on the inside of the bag. When the liners folded and constructed in accordance with my invention are used with round barrels, which is the most frequent use, it is advisable to position the lines of fold 3 approximately one-fourth the distance from the edge seam across the bag so that when the liner is opened out it will be substantially square.

When the liners are folded, they may be readily inserted within a barrel because they are of less width than the inside diameter of the barrel. When a liner is inserted within a barrel and material is filled in, the liner will expand without strain evenly around its entire periphery, the infolded portion gradually expanding and conforming to the shape of the barrel. The infolding of the sides and ears is done after the bag is made, and the infolded ears are not secured to the bottom of the bag as in the common grocery bag, thus allowing entire freedom for expansion. This is a very desirable feature as it leaves the bottom of the bag free to expand around its entire periphery both because the stretch of the paper is, through the infolding, made available throughout the periphery of the bottom, and also because the free ears can open out as required to conform to the shape of the bottom of the container in which the liner is designed to fit.

Furthermore, the freedom of the infolded ears to expand is enhanced by the fact that the ears are infolded inside of the liner, and when the lined container is filled the tendency of the material is to push the ears outwardly so that they naturally conform to the shape of the container. In some earlier forms of bag type liners, ears which were folded under and laid against the outside of the bag were provided, but such folding did not, of course, provide portions which would expand naturally with the filling of the container, as the incoming material pressed the ears between the bottom of the liner and the rough bottom of the container, thereby hindering expansion.

Another advantage in my new type of liner is that, due to the infolding of the ears on the inside of the liner, the bottom seam is

practically covered, and there is much less sewn seam exposed than with any other type of liner. This is advantageous because the sewn seams are ordinarily the weakest part of the liner and the part most subject to siftage or penetration through the needle holes.

Summing up the advantages of my new liner, it is very easy to open out because it has no folds that retard natural expansion. It 10 may be said to balloon out to fit the barrel. When folded for shipment it is folded flat, and it is then of such size that it will readily slip within the head of the barrel. By making the liner slightly wider than is necessary, 15 the top edges may be quite readily turned down over the chime of a barrel. Finally the infolded ears cover the bottom seam and are free to expand naturally with the filling in of material into the container.

20 Having thus described my invention, what I claim as new and desire to secure by Letters Patent, is:—

1. A liner for a container made of readily stretchable paper formed into a flat bag, with 25 the side edges thereof folded inwardly, and with the lower corner edges folded into the bag and against the bottom of the bag without being secured thereto.

2. A liner for a container made of readily 30 stretchable paper formed into a flat bag, with the side edges thereof folded inwardly, and with the lower corner edges folded freely into the bag and against the bottom of the bag, thereby providing a liner which will be free 35 to expand about its entire periphery.

3. A bag liner for containers, having the lower corner edges thereof folded inwardly and laid freely against the inside of the bottom of the bag.

40 4. A method of folding a barrel liner so that it will be free to expand and conform to the shape of a barrel, which consists in folding the side edges inwardly and tucking the lower corner edges of the bag against 45 the inside of the bottom thereof without securing them thereto.

50 5. A process of making a barrel liner, which consists in folding a sheet of readily stretchable paper and stitching the meeting edges together where the edges of the sheet meet both at the side and at the bottom, and then folding in the side edges of the bag thus formed and tucking the lower bottom corners inwardly against the inside of the bottom of 55 the bag without securing them thereto.

60 6. A barrel liner of the flat bag type having a stitched seam at the bottom, with the lower corner edges of the bag folded freely into the interior of the bag so as to cover the stitched bottom seam.

65 7. A barrel liner of the flat bag type and with a bottom seam, having ears at the bottom of the liner folded inwardly so as to lie within the bag above the bottom seam, but 70 unsecured thereto.

8. A liner for a container made of readily stretchable paper formed into a flat bag, with the lower corner edges folded freely into the inside of the bag and against the bottom of the bag, thereby providing a liner which 75 will be free to expand about its entire periphery.
